INVENTOR:

Rein Stahl.

UNITED STATES PATENT OFFICE.

KARL STAHL, OF FRIEDRICHSHAFEN, GERMANY, ASSIGNOR TO THE FIRM LUFT-SCHIFFBAU ZEPPELIN GESELLSCHAFT MIT BESCHRANKTER HAFTUNG, OF FRIEDRICHSHAFEN, GERMANY.

KEYBOARD DEVICE FOR AIRCRAFT.

Application filed June 28, 1920. Serial No. 392,596.

(GRANTED UNDER THE PROVISIONS OF THE ACT OF MARCH 3, 1921, 41 STAT. L. 1313.)

To all whom it may concern:

Be it known that I, KARL STAHL, a citizen of Germany, residing at Friedrichshafen a/B., Germany, have invented certain new and useful Improvements in Keyboard Devices for Aircraft (for which I have filed application in Germany on August 7, 1916, Patent No. 300,603), of which the following is a specification.

10 My invention refers to air-craft, and more particularly to a key-board device suitable for air-craft, and more especially for air-ships. Air ships possess numerous appliances for the purpose of regulating and altering its bearing-capacity at will, such as tanks for discharging ballast and valves governing the escape of bearing-gas. The commander of the air-ship must be able to bring into operation all these various appliances, distributed over the whole of the air-ship, at any moment. For this reason the valves, ballast-tanks, etc., are connected with a key-board device fitted in the car of the commander, by means of traction wires or some other medium for operating at a distance, so that they can be worked separately and independently from the key-board. Such a key-board can be employed in a similar manner for the purpose of dropping signal-rockets or bombs, or of opening the cages of carrier-pigeons or ripping seams, or of operating certain search-lights, etc.

As the number of devices requiring manipulation and the variety of their distribution over the whole air-ship grows, the difficulty of avoiding mistakes possibly entailing consequences of the most serious nature, and of working the valve of a certain balloon cell for instance, or the discharging device of a certain ballast-tank with certainty and without loss of time in moments of danger, increases proportionately for the commander of the airship. Marking the levers, keys and handles with letters of the alphabet, numbers or similar designations denoting the what and the where of the respective devices attached to them, does not offer sufficient security against misapprehensions.

50 It is the object of my invention to elimi-

nate the danger of mistakes in a manner which does not strain the memory in any way.

Therefore my invention consists in a key-board device specially suited for air-ships, 55 this key-board device being characterized by comprising a sketch, picture, copy or model or illustration of some kind of the air-ship. According to my invention those parts of the air-ship and its appurtenances which 60 are worked from the key-board, such as devices for emptying gas, cells and for governing the discharge of ballast, are marked separately and individually in the place corresponding to their respective positions in 65 the air-ship. In supplementing my invention the traction wires or keys serving to work the device, are arranged to suit the above.

The drawings attached to this specification 70 and forming part thereof, illustrate by way of example two modifications of my invention. In the drawings—

Fig. 1 is a front view of a simple key-board device fitted on the wall of a car. 75

Fig. 2 is a cross-section of the key-board in the plane 2—2 of Fig. 1, whilst

Fig. 3 is a cross-section of a key-board device fitted under the roof of a car in such a manner as to coincide with the central plane 80 of the car.

In the example illustrated in Figs. 1 and 2 a box-shaped body B is fitted on the port side of the car, but somewhat higher than the real wall of the body A of the car, approximately on a level with the eyes. The front of the box B is formed by a plate of ground glass C which should preferably have an inclination. An elevation c' of the air-ship showing the distribution of space 90 is delineated on the ground glass plate. Now let us assume that the bearing body of the air-ship in its lower portion contains 24 ballast tanks arranged in pairs and symmetrically with regard to the keel line. 95 Accordingly the diagrammatical sketch c' shows 12 markings c² which it is advisable to number to correspond and which should preferably be entered exactly on the spots in the diagram tallying with the position 100

of the respective pairs of ballast-tanks in the real air-ship. The valves of these tanks are connected with the key-board by two groups *d* and *e* of 12 traction wires each.

- 5 The vertical key-board ends of the traction wires are brought down in pairs behind the markings *c*² in such a way that each pair of traction wires is accurately in position behind the pertinent marking *c*². As 10 a further measure of safety the traction wires are guided in the top and bottom walls of the box. Handles (*d*' and *e*') form the end of every traction wire. The handles *d*' corresponding to the starboard ballast- 15 tanks are arranged directly below the inner part of bottom *d*' of the box which is designed with two steps. The handles *e*' for the port tanks are arranged under the lower part of the bottom of the box, this part 20 being the one nearest the wall of the car.

A lighting arrangement (not shown) provided in the inside of the box, makes it possible to use the diagram *c*' in the dark.

If the key-board is only used for controlling the ballast-tanks and if all the various points controlled are fitted up alike, as was assumed in this example, then there is no need to characterize the various markings *c*² in a particularly striking manner. A 25 more accurate differentiation, however, becomes imperatively necessary, if, for instance, large ballast-bags which are usually only discharged gradually, and ballast-tanks 30 designed to be emptied separately and completely in a moment, are provided besides ballast-casks, which can be dropped separately as pieces in the case of sudden danger occurring. Such a differentiation is achieved, according to my invention, through 35 a reference to the peculiar function fulfilled by each device under control of the key-board being embodied in the pertinent markings either by pictorial or by spatial means. It is therefore advisable that the markings 40 *c*² should contain pictorial representations of a ballast-cask, a ballast-tank for momentary discharge or a ballast bag, as the case may require.

For further safety the handles *d*' and *e*' 45 may have a shape corresponding to that of the various containers of ballast. A differentiation after this manner increases in value as the variety of functions fulfilled by the devices under the control of the key-board grows in number. If, for instance, 50 valves and ripping seams for slow or quick discharge, respectively, of cells are to be controlled from the key-board too, and perhaps search-lights and signal rockets besides, then an extensive differentiation becomes absolutely necessary. In such a case 55 it appears advisable to employ not only the sense of shape, but also the sense of colour as help in finding the various devices quickly 60 on the key-board. This may be done by

colouring all the markings for dropping ballast black, all those for emptying gas-cells red, all those referring to optical signalling green for instance.

Selection among the handles provided on 70 the key-board is further facilitated, according to my invention, by the arrangement of the handles in groups and rows, respectively, besides employing colours for the purpose as described above. A useful arrangement 75 of the handles, for instance, consists in locating the handles controlling the gas-cell valves and the ripping seams in the uppermost rows, those working the devices for the discharging of ballast in the intermediate rows, whilst those governing the bomb-dropping apparatus range in still lower rows etc. In this way it is also possible to arrange the controlling apparatus for all 80 the various devices in such succession that 85 it agrees with the actual facts and with the representation given in the diagram on the key-board. A further advantage gained by such a grouping as described, consists in keeping the size of the key-board down and 90 in not being obliged to reduce the size of the handles, keys, etc., too far.

By means of such a key-board arrangement a commander, on taking command of 95 an air-ship, can tell immediately and with a single glance what means for fulfilling a given purpose he has available in the various parts of his vessel.

In order to retain a clear view of affairs 100 even on a long trip and after various using 100 of some of the devices has taken place, without having to rely on memory, indicating contrivances are provided in accordance with the invention. These indicating contrivances come into action as soon as the pertinent handle is pulled; they announce 105 whether a certain ballast-tank for momentary discharge has been pulled, i. e., emptied, or whether a certain bomb has been 110 dropped, or whether the rear lights are 110 switched off or on, etc. As far as devices are concerned which are only operated once, such as those for dropping ballast-casks, etc., the indicating contrivance can consist 115 simply of a signal plate which covers up the marking in the diagram on the key-board or some other means of characterizing the marking in question as being no longer available. If, however, devices used 120 repeatedly, such as the valves of ballast bags for instance, are under consideration, then the indicating contrivance must give information as to how much the device in question can still be used; a shifting scale or something similar would comply with the 125 case. The detailed design of the contrivances indicating whether a certain device has already been used or not, depends on the purpose to which the device in question 130 is devoted and does not form part of this 130

present invention. For this reason these indicating contrivances are not included in the drawings.

Instead of employing only a pictorial representation of the air-ship, a model may also be used which it is advisable to make transparent and locate in the central plane of the car. This second example will be readily understood from the drawing Fig. 3 in connection with the above explanations. Such a model is recommended especially for cases where more than two devices which have to be operated from the keyboard, are contained in one and the same cross-section or where devices are concerned which are only used in the most extreme danger and then only in groups, if possible.

My invention is not restricted to use in air-ships only. It can be applied most advantageously for instance to the modern giant flying machines with their manifold devices for signalling, dropping, as well as working and controlling their plant and appliances.

I claim:

1. In an aircraft in combination, a plurality of appliances adapted to be actuated from a distance, a control board, a reproduction of the craft connected with said control board means connected with said reproduction for marking thereon the positions of said appliances in the craft and means extending in front of each mark for actuating one of said appliances.

2. In an aircraft in combination, a plu-

rality of appliances adapted to be actuated from a distance, a control board, a reproduction of the craft connected with said control board means of different configuration connected with said reproduction for marking thereon the positions of said appliances in the craft and means extending in front of each mark for actuating one of said appliances.

3. In an aircraft in combination, different groups of appliances adapted to be actuated from a distance, a control board, a reproduction of the craft connected with said control board, separate means of different configuration connected with said reproduction for marking thereon the positions of the different groups of appliances in the craft and means extending in front of each mark for actuating one of said appliances.

4. In an aircraft in combination, different groups of appliances adapted to be actuated from a distance, a control board, a reproduction of the craft connected with said control board, separate means of different configuration connected with said reproduction for marking thereon the positions of the different groups of appliances in the craft, means extending in front of each mark for actuating one of said appliances and means connected with said reproduction for indicating the operative condition of each appliance.

In testimony whereof I affix my signature.

KARL STAHL.
